(57) **CLAIM**

The ornamental design for a screw-operated syringe ink bottle, as shown and described.

DESCRIPTION

FIG. 1 is a perspective view of a screw-operated syringe ink bottle showing my new design;
FIG. 2 is a front elevation view with a cap attached thereof, the rear elevational view being a mirror image;
FIG. 3 is a front elevation view without a cap attached thereof, the rear elevational view being a mirror image;
FIG. 4 is a right side elevational view with a cap attached thereof, the left side elevational view being a mirror image;
FIG. 5 is a right elevational view without a cap attached, the left side elevational view being a mirror image;
FIG. 6 is top plan view thereof; and,
FIG. 7 is a bottom plan view without a cap attached thereof. The broken line showing of a cap in FIGS. 2 and 4 is shown to represent environment only.
